(57) **CLAIM**

The ornamental design for an auto-return batting tee, as shown and described.

DESCRIPTION

FIG. 1 is a perspective view of an auto-return batting tee showing my new design;

FIG. 2 is a left side elevation view thereof;

FIG. 3 is a right side elevation view thereof;

FIG. 4 is a front elevation view thereof;

FIG. 5 is a rear elevational view thereof;

FIG. 6 is a top plan view thereof; and,

FIG. 7 is a bottom plan view thereof.

The broken line showing of the ball is for illustrative purposes only and forms no part of the claimed design.
